UNITED STATES PATENT OFFICE.

WILLIAM WATTIE, OF WORCESTER, MASSACHUSETTS, ASSIGNOR TO CROMPTON & KNOWLES LOOM WORKS, A CORPORATION OF MASSACHUSETTS.

VIBRATOR-LEVER AND VIBRATOR-CONNECTOR.

1,112,874.

Specification of Letters Patent.

Patented Oct. 6, 1914.

Application filed December 15, 1910. Serial No. 597,469.

To all whom it may concern:

Be it known that I, WILLIAM WATTIE, a citizen of the United States, residing at Worcester, in the county of Worcester and State of Massachusetts, have invented certain new and useful Improvements in Vibrator-Levers and Vibrator-Connectors, of which the following is a specification.

My invention relates to a vibrator lever, and a vibrator connector, which form a part of the well known Knowles head motion for shuttle box and harness shedding mechanism of looms, shown and described in U. S. Reissue Letters Patent, No. 7,784.

My invention particularly relates to an improved construction of the vibrator lever, and vibrator connector. The vibrator lever, and vibrator connector referred to, are ordinarily made of malleable iron, with the bosses and forked ends cast thereon, and must be made quite thin in order to take up as little room as possible, and consequently these parts are liable to break very easily.

The object of my invention is to improve upon the construction of the vibrator lever, and vibrator connector above referred to.

My improved vibrator lever, and vibrator connector are made of sheet metal, preferably steel, which is punched or cut out in the desired shape, without the studs or bosses, and the reinforced part formed thereon; said studs or bosses, and the reinforced part are made separate and rigidly connected with the vibrator lever, and vibrator connector, to be practically integral therewith, by welding.

I have shown in the drawing a detached part of a Knowles head motion of the type referred to, comprising a vibrator lever, a vibrator gear pivotally mounted on said lever, and a vibrator connector pivotally attached to said gear.

Referring to the drawing:—Figure 1 is a side view of my improved vibrator lever, and a vibrator gear pivotally mounted thereon, and my improved vibrator connector attached to said gear. Fig. 2 shows the blank from which the vibrator lever shown in Fig. 1 is made. Fig. 3 shows the boss of the vibrator lever detached. Fig. 4 shows a patch piece to be attached to the blank. Fig. 5 shows the engaging end piece, detached. Fig. 6 shows a top and side view of a stud or boss to be secured to the blank. Fig. 7 is an edge view of the vibrator lever

shown in Fig. 2, looking in the direction of arrow *a*, same figure, with the bosses and the patch pieces thereon, preparatory to being welded. Fig. 8 shows the blank from which the vibrator connector shown in Fig. 1 is made. Fig. 9 shows a blank for the reinforced slotted end of the vibrator connector. Fig. 10 shows a boss or stud for the attaching end of the vibrator connector. Fig. 11 is an edge view of the vibrator connector, looking in the direction of arrow *b*, Fig. 8, with the boss and reinforced slotted end thereon, preparatory to being welded.

In the accompanying drawing, 1 is the vibrator lever blank, cut or stamped out of sheet metal, having in this instance a pattern run 2, made separate therefrom and riveted thereon, on its lower edge, in the usual way. A boss or pivot stud 3, see Fig. 1, is secured upon the blank 1, and carries, loosely mounted, to have a reciprocating or rocking movement, a vibrator gear 4. The gear 4 has a curved slot 4' therein, to receive a boss 5 on the vibrator lever 1.

6 is the vibrator connector, which is pivotally attached to the vibrator gear 4 by the boss 7, all in the usual and well known way.

I will now describe my improvements in vibrator lever, and vibrator connector above referred to.

The vibrator connector 1 is first preferably punched or cut out of sheet metal, preferably steel in the shape shown in Fig. 2, having the open end slot portion 1', to which is to be attached the boss piece 8, Fig. 3, of corresponding shape. The boss piece 8 is attached to the blank 1 at 1', as shown in Fig. 7. A bar or piece 9, Fig. 4, is also to be attached to the blank 1, near the open end slotted portion 1', as shown in Figs. 1 and 7. The opposite end 1'' of the blank 1 receives the piece 10, Fig. 5, of corresponding shape, as shown in Figs. 1 and 7.

The blank 1 is provided with two holes or openings 1^a and 1^b, which in this instance are the places where the bosses 3 and 5, see Fig. 1, are located. The bosses 3 and 5 consist of a hub piece 11, shown in Fig. 6, which is provided with the reduced end 11', adapted to be inserted into the bore 1^a, 105 or 1^b.

The blank 1 is held in a suitable device, with the separate bosses and pieces in place thereon, and each separate boss and piece on the blank 1 is welded to said blank,

and the vibrator lever 1 then appears as if it were made of a single piece, with the exception of the run 2, as shown in Fig. 1.

The vibrator connector is made in the same manner as the vibrator lever 1, above described. The blank 6 is punched or cut out of sheet metal, preferably steel, in the shape shown in Fig. 8, with an open end slot 6' at one end. The offset reinforced 10 end piece 12, see Fig. 9, with an open end slot 12' therein, is made in this instance separately, to be attached to the blank 6. The hole 6^a in the blank 6, in the opposite end thereof, is adapted to receive the reduced end on the hub piece 13, see Fig. 10, which is similar to the bosses 5 and 6, attached to the blank 1 of the vibrator lever.

The boss 13, and piece 12 on the vibrator connector blank 6 are welded to the blank 6, and the vibrator connector then appears as if it were made of a single piece, as shown in Fig. 11.

My improved vibrator lever, and vibrator connector require considerable less stock, 25 and are of greater strength and rigidity than the ordinary malleable iron vibrator lever, and vibrator connector.

It will be understood that the details of construction of my improved vibrator lever, 30 and vibrator connector may be varied if desired.

Having thus described my invention,

what I claim as new and desire to secure by Letters Patent is:—

1. As an improved article of manufacture, 35 a vibrator lever for the head motion of a loom shuttle box and harness shedding mechanism, comprising a single piece of sheet metal of one thickness, made in the desired shape, with an open end slot at one end, and a separate piece, having an open end slot therein, and welded thereto at said open slot end, to form a double thickness of metal, and a stud or boss, made separate, and welded to the other end of said piece 45 of sheet metal.

2. As an improved article of manufacture, a vibrator connector for the head motion of a loom shuttle box and harness shedding mechanism, comprising a single piece of 50 sheet metal of one thickness, made in the desired shape, with an open end slot at one end, and a separate piece, having an open end slot therein, and offset, and welded thereto at said open slot end, to form two 55 thicknesses of metal, with a space between, and a stud or boss, made separate, and welded to the other end of said piece of sheet metal.

WILLIAM WATTIE.
